UNITED STATES PATENT OFFICE.

JOHN J. THACHER, OF ATTLEBORO, MASSACHUSETTS, ASSIGNOR TO BROWN AND SHARPE MANUFACTURING COMPANY, OF PROVIDENCE, RHODE ISLAND, A CORPORATION OF RHODE ISLAND.

WORK-REST FOR GRINDING-MACHINES.

No. 779,214.

Specification of Letters Patent.

Patented Feb. 18, 1908.

Application filed September 26, 1905. Serial No. 279,901.

To all whom it may concern:

Be it known that I, JOHN J. THACHER, of Attleboro, in the county of Bristol and State of Massachusetts, have invented certain new and useful Improvements in Work-Rests for Grinding-Machines; and I do hereby declare the following specification, taken in connection with the accompanying drawings, forming a part of the same, to be a full, clear, and 10 exact description thereof.

The invention relates to work rests for supporting the work in grinding machines against the action of the grinding wheel and its primary object is to provide a construction 15 in which the relative position of the bearing blocks which bear against the work may be readily and conveniently changed to adapt the rest for work of different diameters.

To this end the invention consists in the 20 features and combinations hereinafter described and specified in the claims.

The various features of the invention will be readily understood from the following detailed description of the construction in 25 which I have embodied them and which is shown in the accompanying drawings.

In these drawings—Figure 1 is a sectional elevation of a grinding machine work rest provided with the present improvements; 30 Fig. 2 is an enlarged side elevation of a bearing block arm embodying my invention; and Fig. 3 is a front elevation of the same.

In the accompanying drawings the features of the present invention are shown in 35 connection with a work rest having the same general construction as the work rest shown in Patent No. 732,314 dated June 30, 1903. This work rest comprises a base A adapted to be secured in position upon the machine 40 and carrying a supporting carriage B upon which the bearing block arm C is pivoted. The supporting carriage B is supported and guided upon a roll B' and is held yieldingly in position by the action of a spring B² upon a 45 lever B³, the upper end of which is pivoted to the rear part of the supporting carriage. The forward movement of the supporting carriage is limited and determined by an adjustable stop screw B⁴ mounted in the 50 lever B³ and arranged to engage a part of the base A.

The bearing block arm C is provided with 55 trunnions C' adapted to engage bearings formed in the bifurcated forward end of the supporting carriage B. The bearing block

arm is held in position by the engagement of its rear arm C² with the end of an adjustable screw rod B⁵. The screw rod is forced yieldingly forward by means of a spring B⁶ arranged within a recess in the carriage B and between two nuts B⁷ B⁸. The nut B⁷ is threaded on the rod B⁵ and is held from rotation by a pin B⁹ while the nut B⁸ is screw-threaded in the supporting carriage B and may be adjusted to vary the tension of the spring B⁶. The spring B⁶ holds the nut B⁷ against the forward end of the recess in the supporting carriage B and thus determines the forward position of the bearing block arm while holding it yieldingly up to 70 the work.

The bearing block arm C is provided with a fixed bearing block C³ which may be formed integral with the arm or may be a separate block secured thereto and which is arranged 75 to engage the rear side of the work substantially opposite the point of engagement of the grinding wheel with the work. The bearing block arm is also provided with a second bearing block C⁴, arranged to engage the 80 under side of the work and this block is so connected with the arm C that it may be adjusted in an inclined or diagonal direction toward or away from the fixed bearing block C³. In the form of bearing block arm shown, 85 the adjustment of the bearing block C⁴ is provided for by mounting the block upon a bar C⁵ which extends downward and forward in an inclined direction from below the bearing block C³. The bearing block C⁴ is recessed 90 to fit and slide upon the bar C⁵ and is held in adjusted position thereon by means of a binding screw C⁶.

By adjusting the bearing block C⁴ toward the bearing block C³ the block C⁴ is moved upward toward the horizontal plane passing through the bearing block C and is also moved rearwardly so that it will be substantially beneath the center of a piece of work which is of such a diameter that it will be engaged by the bearing blocks when its center is substantially in front of the bearing block C³. Thus by a simple adjustment of the bearing block C⁴ the relative position of the bearing blocks upon the arm C is changed to adapt the bearing block arm for use with different sizes of work and at the same time the proper position of the bearing blocks with relation to the center of the work is maintained.

When the bearing block C⁴ has been ad- 110

justed to correspond to the diameter of the work which is to be operated upon, the bearing block arm may be brought into proper position with relation to the work by operating the screw B⁴ to move the supporting carriage B forward or back as the case may be.

While I prefer to mount the bearing block C⁴ in the manner shown in the drawings, it will be understood that the specific construction whereby the bearing block is adjustably supported so that it may be moved toward or from the fixed bearing block in an inclined direction, may be varied as desired.

What I claim and desire to secure by Letters Patent is:—

- 15 1. A work rest for grinding machines comprising a support, an inclined arm connected thereon, a fixed bearing block on said arm, and a second bearing block thereon mounted 20 for adjustment on an inclined arm toward and away from the fixed bearing block.
2. A work rest for grinding machines comprising a support, an inclined bearing block arm pivoted thereon, a fixed bearing block 25 on the arm arranged to bear against the rear of the work, a second bearing block arranged to bear against the under side of the work

and adjustable on said inclined arm toward and away from the fixed bearing block.

3. An inclined bearing block arm for grinding machine work rests provided with a fixed bearing block for bearing against the rear of the work, and with a bearing block for bearing against the under side of the work adjustable on said inclined arm towards and 35 away from the fixed bearing block.

4. A bearing block arm for grinding machine work rests provided with a fixed bearing block for bearing against the rear of the work, a guiding support extending forward 40 in an inclined direction from the rear bearing block, and an under bearing block adjustably connected with said support.

5. A bearing block arm for grinding machine work rests constructed to be pivotally 45 supported and provided with a fixed rear bearing block and a bar formed integral therewith, said bar projecting in an inclined direction below the rear block and an under bearing block adjustably secured to the bar. 50

JOHN J. THACHER.
